UNITED STATES PATENT OFFICE

EDWARD F. DUDLEY, OF OAK PARK, ILLINOIS, ASSIGNOR TO THE MIEHLE PRINTING PRESS & MANUFACTURING CO., OF CHICAGO, ILLINOIS, A CORPORATION OF ILLINOIS

INKING MECHANISM

Application filed July 11, 1929. Serial No. 377,396.

This invention relates to inking mechanism for printing presses and the like machinery where an evenly distributed film of ink has to be applied to the type matter or 5 printing plate from which impressions are to be taken.

The invention relates particularly to that type of inking mechanism covered in the co-pending U. S. patent application, Serial No. 10 285,258 where a metal drum of a comparatively large diameter is used as an ink distributing means in place of an ink distributing table such as are commonly known in the art.

15 One of the principal problems in the art of printing, is that of obtaining proper ink distribution, especially where quality work is required. In order to secure satisfactory results, it is essential to apply an exceedingly 20 evenly distributed film of ink to the form of the press.

The primary object of my invention, therefore, is to provide an improved inking mechanism, whereby an extremely efficient distribution of the printing ink is made possible.

25 Another object of the invention is to provide an inking mechanism comprising an ink distributing unit, the cooperating parts of which constantly rotate in given directions 30 so that the film of ink distributed thereover will not be interrupted at any time during the ink applying period.

A further object of my invention is to provide improved inking mechanism comprising 35 a novel combination of an ink distributing plate for the purpose of adapting the inking mechanism more especially for use in connection with such forms which require an exceptionally heavy and yet even application of 40 ink.

Still further objects of the invention will be apparent from the following description and appended claims.

The invention is diagrammatically illustrated in the accompanying drawings in which:

Figure 1 shows the position of the cooperating parts at that time of the printing cycle when a film of ink is conveyed from the ink 50 distributing unit to the form on the bed of

the press during the non-printing stroke of the bed, i. e. when it returns from its preceding printing stroke;

Figure 2 shows the relative position of the parts during the impression i. e. printing 55 stroke of the bed; and

Figure 3 illustrates a modified arrangement of the parts as will be hereinafter described.

It is understood that motion is imparted to 60 the various parts of the inking mechanism in accordance with the usual practice in the construction of printing presses.

The type bed 10, which carries the form or type matter from which impressions are to be 65 taken, is reciprocated in a known manner to and fro beneath the impression cylinder 11. The particular type of printing press in connection with which the invention is illustrated merely by way of example, is a two- 70 revolution press wherein the impression cylinder constantly rotates in one direction and performs two revolutions for every impression cycle of the press.

The ink is stored in an ink fountain 12 of 75 usual construction and comprises a fountain roller 13 from which ink is intermittently transferred to the ink distributing drum 14 by means of a ductor roller 15. In order to distribute the ink over the drum 14, one or 80 more rider rollers 16 are arranged in contact with said drum. The latter is preferably vibrated longitudinally of its axis to assure the best possible distribution of ink thereon.

The film of ink distributed over the surface of the drum 14 is transferred to the form roller unit by means of a ductor roller 17 which remains in constant contact with the surface of the drum 14 but oscillates over said drum to intermittently apply a thin film 90 of ink to the intermediate roller or distributing drum 18, which, according to the particular form of construction shown, is a metal roller.

The form roller unit also comprises a rider 95 roller 19 which cooperates with the intermediate roller or drum 18 to convey the ink therefrom to a steel vibrator roller 20. The latter contacts with the form rollers 21 and 22, which preferably have different diam- 100

eters, and owing to the lateral vibratory motion of the roller 20 the ink will be subjected to a final distribution before it reaches the printing form.

5 In order to assure the best possible distribution of ink before it reaches the form rollers 21 and 22, two additional rider rollers 23 and 24 may be provided to cooperate with the rider roller 19 and vibrator roller 20.

10 For the purpose of more especially adapting the herein described inking mechanism in connection with such forms which require an exceptionally heavy and yet evenly distributed supply of ink, I provide an ink distributing table or plate 25 which receives a supply of ink from the drum 14 by means of an additional ductor roller 26.

According to the preferred construction shown in Figures 1 and 2, the ductor roller 26 is arranged to oscillate over the surface of the drum 14 and maintains constant contact therewith. It is of advantage to impart to the roller 26 the same motion as to the ductor roller 17, so that a supply of ink will be transferred from the drum 14 to the plate 25 at the same time when the ductor roller 17 conveys a film of ink from the ink distributing unit to the form roller unit. In the arrangement shown in Figures 1 and 2 the ductor rollers 17 and 26 constantly rotate in one direction as indicated by the arrows, and therefore it is necessary that in this particular case the ductor roller 26 deposits a film of ink on the plate 25 during the non-printing or return stroke of the bed 10.

However, it will be readily understood that the ductor rollers 17 and 26 could be arranged to transmit ink alternately, or in any desired sequence, to the drum 14 and plate 25 respectively, without departing from the spirit of my invention, such alternative arrangement being indicated in Figure 3. In this modified arrangement, it will of course be necessary to arrange the ductor roller 26 so that it will contact with the plate 25 and supply ink thereto during the impression stroke of the bed, at which time the ductor 26 would have to be tripped from the drum 14.

50 Referring to Figure 1 of the drawings, it will be seen that with the prevailing arrangement, a film of ink is transferred from the drum 14 and applied to the form on the bed 10 during the return stroke of the bed, i. e. when the bed moves away from the cylinder 11. At the same time the ductor roller 26 conveys a supply of ink from the drum 14 to the plate 25. When the ductor 26 reaches the edge 27 adjacent the gap 28, provided 55 between the plate 25 and the bed 10, it is tripped and will remain in a tripped i. e. raised position until the form again returns during the next impression cycle of the press. During the impression stroke of the bed 10, 60 the ductor rollers 17 and 26 will be in the

position shown in Figure 2 and any ink that remains stored in the form roller unit, after the bed had reached the end of its non-impression stroke, will then be applied to the form. On the other hand, as the form rollers 21 and 22 pass over the plate 25, they will take up the ink that was previously applied to said plate by the ductor roller 26 and store it in the form roller unit. During the impression stroke of the bed, the ink from the plate 25 stored in the form roller unit, as explained, will be deposited onto the form in addition to the ink transmitted from the drum 14 by the ductor roller 17.

65 In the particular arrangement shown for the purpose of illustrating my invention, the distributing drum 14, which constantly rotates in one direction, makes four revolutions during every impression stroke of the press and rotates at press speed, that is to say, at the surface speed of the impression cylinder. It will of course be readily understood that any other suitable ratio of the number of revolutions made by the drum 14 per impression stroke of the press may be adopted without departing from the principle of the invention.

70 I claim:

1. In inking mechanism for printing presses or the like, the combination of ink distributing roller mechanism, form roller mechanism, an ink distributing plate, and means for conveying ink from said distributing roller mechanism to said form roller mechanism and to said plate. 75

2. In inking mechanism for printing presses or the like, the combination of ink distributing roller mechanism, form roller mechanism, an ink distributing plate, and means in constant contact with said distributing roller mechanism for conveying ink from the latter to said form roller mechanism and to said distributing plate. 80

3. In inking mechanism for printing presses or the like, the combination of ink distributing roller mechanism, form roller mechanism, an ink distributing plate, and means in constant contact with said ink distributing roller mechanism, and having intermittent contact with said form roller mechanism and said plate for conveying ink thereto. 85

4. In inking mechanism for printing presses or the like, the combination of an ink fountain, ink distributing roller mechanism, means for conveying ink from said ink fountain to said distributing roller mechanism, form roller mechanism, an ink distributing plate, and means in constant contact with said ink distributing roller mechanism to convey ink from the latter to said form roller mechanism and to said plate. 90

5. In inking mechanism for printing presses or the like, the combination of an ink fountain, ink distributing roller mechanism comprising a constantly rotating metal drum, 95

- means for conveying ink from said ink fountain to said ink distributing roller mechanism, form roller mechanism, an ink distributing plate, and means in constant contact with said ink distributing roller mechanism 5 to convey ink from the latter to said form roller mechanism and to said plate.
6. In inking mechanism for printing presses or the like, the combination of an ink fountain, an ink distributing drum, means for conveying ink from said ink fountain to said distributing drum, form roller mechanism, an ink distributing plate, and means in constant contact with said ink distributing drum to convey ink to said form roller mechanism and to said plate.
7. In inking mechanism for printing presses or the like, the combination of an ink fountain, an ink distributing drum constantly rotating in one direction, means for conveying ink from said ink fountain to said distributing drum, form roller mechanism, an ink distributing plate, and means in constant contact with said ink distributing drum to 20 convey ink to said form roller mechanism and to said plate.
8. In inking mechanism for printing presses or the like, the combination of an ink fountain, an ink distributing drum constantly rotating in one direction, and making one or more revolutions during every printing cycle of the printing press, means for conveying ink from said ink fountain to said distributing drum, form roller mechanism, an ink distributing plate, and means in constant contact with said ink distributing drum to convey ink to said form roller mechanism and to said plate.
9. In inking mechanism for printing 40 presses or the like, the combination of an ink fountain, an ink distributing drum constantly rotating in one direction, means for conveying ink from said ink fountain to said distributing drum, form roller mechanism, an ink distributing plate, and means in constant contact with said ink distributing drum to convey ink to said form roller mechanism and to said plate, said ink distributing drum making one or more revolutions from the time 45 it receives a supply of ink from said ink fountain until said supply is transferred from said drum to the form roller mechanism and to said plate.
10. In inking mechanism for printing 50 presses or the like, the combination of an ink fountain, an ink distributing drum constantly rotating in one direction, means for conveying ink from said ink fountain to said distributing drum, form roller mechanism, an ink distributing plate, a form carrying member, and means in constant contact with said distributing drum to convey ink to said form roller mechanism and to said plate during the non-impression stroke of said form 55 carrying member.
11. In inking mechanism for printing presses or the like, the combination of an ink fountain, an ink distributing drum, means for conveying ink from said ink fountain to said ink distributing drum, one or more rider 70 rollers cooperating with said distributing drum, form roller mechanism, an ink distributing plate, and ductor rollers in constant contact with said distributing drum to convey ink from the latter to said form roller 75 mechanism and to said plate, said distributing drum, rider rollers and ductor rollers rotating constantly in one direction.
12. In inking mechanism for printing 80 presses or the like, the combination of ink distributing roller mechanism including an ink distributing drum, form roller mechanism, an ink distributing plate, and two ductor rollers in constant contact with said drum and operating in unison to convey ink from said drum to said form roller mechanism and to said plate.
13. In inking mechanism for printing 85 presses or the like, the combination of ink distributing roller mechanism, form roller mechanism, an ink distributing plate, and means for alternately conveying ink from said distributing roller mechanism to said form roller mechanism and to said plate.
14. In inking mechanism for printing 90 presses or the like, the combination of ink distributing roller mechanism including an ink distributing drum, form roller mechanism, an ink distributing plate and two ductor rollers operating to alternately convey ink 100 from said drum to said form roller mechanism and to said plate.
15. In inking mechanism for printing 95 presses or the like, the combination of an ink distributing roller mechanism comprising a drum constantly rotating in one direction, form roller mechanism including a drum having alternate rotation, an ink distributing plate, and means for conveying ink from said distributing roller mechanism to said drum 110 of the form roller mechanism and to said distributing plate.
16. In inking mechanism for printing 105 presses or the like, the combination of ink distributing roller mechanism, form roller mechanism including a plurality of form rollers of different diameter, an ink distributing plate, and means for conveying ink from said distributing roller mechanism to said form rollers and to said plate.

Signed at Chicago, Illinois, this 8th day of July, 1929.

EDWARD F. DUDLEY.
